UNITED STATES PATENT OFFICE.

GEORGE R. NIXON, OF PITTSFIELD, MASSACHUSETTS, ASSIGNOR OF ONE-HALF TO HARRY C. CRAFTS, OF PITTSFIELD, MASSACHUSETTS

STEAM-HEATER.

No. 888,451.

Specification of Letters Patent.

Patented May 19, 1908.

Application filed April 13, 1907. Serial No. 368,004.

To all whom it may concern:

Be it known that I, GEORGE R. NIXON, a citizen of the United States, and a resident of Pittsfield, in the county of Berkshire and State of Massachusetts, have invented a new and Improved Steam-Heater, of which the following is a full, clear, and exact description.

My invention relates to heaters, my more particular object being to provide a heater of simple construction and relative high efficiency, and in which a flowing medium such as steam or hot water, can be made to impart a large proportion of its heat to a pipe extending through the heater.

Reference is to be had to the accompanying drawings forming a part of this specification, in which similar characters of reference indicate corresponding parts in all the figures.

Figure 1 is a side elevation showing one form of my heater used in connection with a kitchen boiler for the purpose of heating water therein; Fig. 2 is an enlarged central section through the heater and showing the internal arrangement of the latter; Fig. 3 is a side elevation showing my heater in a slightly different form as applied to a kitchen boiler for the purpose of heating water therein, the heater being connected with a gas heater so that heat may be supplied to the water in the boiler from either or both of two independent sources; and Fig. 4 is a side elevation somewhat similar to Fig. 3, but showing how my heater and a gas heater are connected with a radiator and with a kitchen boiler for the purpose of heating the kitchen and of supplying hot water thereto.

A pipe 5 which may be of brass or other preferred metal, is encircled by a tube 6, having a threaded end 7, upon which is screwed a dome-shaped fitting 8, provided internally with a thread 9 for the purpose. A somewhat similar dome-shaped fitting 10, is provided internally with a thread 11 and is screwed upon the opposite end of the tube 6.

An asbestos jacket 12 of tubular form, neatly encircles the tube 6, and serves as an outer casing for the heater and also to distribute and conserve the heat. Stuffing boxes 13 are carried by the fittings 8 and 10 and encircle the pipe 5; this arrangement allows for expansion and contraction of the various parts. An air-valve shown at 14, may be used for either letting off gases or steam or for admitting air as desired.

The mechanism shown in Fig. 2 constitutes the heater as a whole; this mechanism is connected with a steam pipe 15 as indicated in Fig. 1, and from the heater steam pipe sections 16, 17 connect up with the boiler. A pipe 18 leads upwardly from the pipe section 17. A pipe 20 is in communication with the heater and with the boiler, and is provided with a valve 21 whereby it may be used as a draw-off.

In the form shown in Fig. 3, the boiler 23 is connected with a pipe 24, which is provided with a coiled portion 25 within a gas heater 26, and this coiled portion is connected with my heater by pipe sections 27, 28. A pipe 29 leads from the heater to the boiler 23. A valve 30 is used for drawing off water from the pipe 28. Brackets 31 engage the jacket 12 for the purpose of supporting the heater; steam pipes are shown at 32 and 33, and are used for the purpose of passing steam through the heater.

In the form shown in Fig. 4, a radiator 34 is connected with my heater by a pipe 35, and the heater is connected by pipe sections 36, 37 with the boiler 32. A pipe 38 leads upwardly and is provided with a coiled portion 39 within a gas heater 46. This coiled portion 39 is connected by a pipe 41 with the boiler 23.

The form of my device shown in Fig. 1 may be used in almost any place where it is desired to have steam heat the boiler 19.

In the form shown in Figs. 3 and 4 my heater may be employed in the winter-time, whereas the gas heater 26 or 46 may be used for heating in the summer-time. These two figures show the manner in which my heater may be used alternately with a gas heater.

Referring more particularly to Fig. 2, it will be noted that my heater is exceedingly simple in construction, and that owing to the use of the stuffing boxes there can be no breaking, discharge or leakage easily caused by the expansion or the contraction of any or all of the various parts.

Having thus described my invention I claim as new and desire to secure by Letters Patent:—

A device of the class described comprising in combination a water pipe, a tube of greater internal diameter than the external diameter of the pipe and co-axial therewith, dome-shaped fittings threaded onto the ends of the tube, one of said fittings being pro-

vided with a steam supply opening and the other with an air valve, means for securing packing between the fittings and the pipe; and an asbestos jacket surrounding the tube, the fittings being of greater external diameter than the tube and forming shoulders engaging the jacket at its ends.

In testimony whereof I have signed my name to this specification in the presence of two subscribing witnesses.

GEORGE R. NIXON.
